[57] CLAIM

The ornamental design for an archery bowstring peep sight, as shown and described.

DESCRIPTION

FIG. 1 is an environmental elevational view of an archery bowstring peep sight showing my new design; FIG. 2 is an environmental, elevational view thereof, drawn to an enlarged scale;

FIG. 3 is a right side elevational view thereof;

FIG. 4 is a rear elevational view thereof;

FIG. 5 is a top view thereof;

FIG. 6 is a bottom view thereof;

FIG. 7 is a front elevational view thereof; and,

FIG. 8 is a left side elevational view thereof.

The broken line showing of a bow, arrow, bowstring and bow mounted peep sight in FIG. 1 is for illustrative purposes only and forms no part of the claimed design. The broken line showing of a portion of a bowstring and a bead weight in FIG. 2 is for illustrative purposes only and forms no part of the claimed design.
